APPARATUS FOR VIBRATING THE BLADES
OF SAFETY-RAZORS

Richard Jaffé, Sorengo-Lugano, Switzerland

Application September 7, 1934, Serial No. 743,117
In Germany September 11, 1933

2 Claims. (Cl. 30—44)

Safety razors with relatively movable razor blades therein which are reciprocated during the shaving operation by means of a motor or the like in the direction of the longitudinal cutting edges for the purpose of obtaining improved cutting action, are known.

The present invention relates to a vibrating device for producing the same effect in safety razors with a fixed blade as is obtained in razors with movable blades. The vibrating device according to the invention consists in imparting to the safety razor with fixed blade, in addition to the manually effected movement, at least one supplementary vibratory movement whereby the razor and its blade have imparted thereto the cutting movement resulting from these movements.

The device consists of an apparatus for producing vibratory movements, said apparatus being held with the same hand as the safety razor, so that it transmits its vibrations to the hand and thus to the safety razor.

The device may also be directly connected with the safety razor. It may be actuated by a spring-actuated clock mechanism or by a small motor or the like.

An illustrative embodiment of the device for producing the vibratory movement is shown on the drawing.

30 Fig. 1 is a longitudinal section of a device disposed in the handle of a safety razor, and having a catch-actuated weighted pendulum.

Fig. 2 is a plan view of the device after removal of the upper closure cap.

35 Fig. 3 is a longitudinal section of the device driven by means of an electric motor and centrifugal pendulums arranged in the handle.

Fig. 4 is a view of the casing containing the driving mechanism affixed to a hand razor.

40 Fig. 5 is a plan view thereof.

Fig. 6 is a longitudinal section of the device with a monolateral oscillating weight.

Arranged in an elongated casing 1 provided with a closure cap 2, concentrically about a shaft 3 which is provided with a double winged nut 4 at the end thereof which projects beyond the casing 1, are spring housings 5 which serve to receive spiral springs 6. The spring housings 5 are provided with bosses 7 which have hooks 8 upon which are mounted the inner spring ends 9.

The outer spring end 10 is attached to hooks 11, which are fixed to the inner periphery of the spring housing. The lowermost spring is attached by its inner end to hook 12 which is fixed 55 on shaft 3. By turning shaft 3 by means of the

winged nut to the right, the springs 11 are tensioned gradually, ratchet wheel 13 preventing retrograde movement. The uppermost spring housing 14 is provided with a gear 16 on its boss 15, said gear engaging wheel 18 journaled in false bottom 17, pawl wheel 20 being fixed on axis 19. This moves the pawl 21 which reciprocates the oscillating lever 22 with weight 23. The latter impacts against points 24 of the casing closure cap 2 and vibrates the latter and the casing 1. The upper end of shaft 3 is rotatably journaled in bottom 17 so that gear 16 may cooperate freely with wheel 18. A slide 25 enables the impact mechanism to be started and stopped.

According to this embodiment, the razor 26 of conventional construction is attached to the casing closure cap 2 by means such as a connecting piece 27, and the vibrations produced in casing 1 which serves as the handle are directly transmitted to the razor 26.

In the second embodiment illustrated in section in Fig. 3, an electric motor drives the driving shaft 3. The winding of motor 28 is fixed in casing 1, which functions as the handle, while the armature 29 thereof is securely connected with shaft 3 and drives the latter when electric current is supplied. Fixed to shaft 3 is a gear 16 which engages gear 18. This is securely mounted on spindle 30 which carries the pendulums 31. The latter is rotatably journaled in false bottom 17. Upon rotation of pendulum 31, these pendulums impact against the wall of casing closure cap 2, as a result of the centrifugal force, and set the closure and the razor connected thereto in vibration.

According to the embodiment shown in Figs. 4 and 5, the oscillation-producing vibration device 32 is secured to the razor 34 by two bands 33, and transmits the oscillations thereto.

Fig. 6 shows the fourth embodiment. Arranged in casing closure cap 2 is an eccentrically mounted, heavy, unbalanced rotational mass 35, which is rotatably journaled in the false bottom 17 and is driven from the drive shaft 3 through the medium of gears 18 and 16, whereby it is 45 rotated. The mass 35 bumps against the wall of the casing closure cap 2, thereby oscillating the latter together with the entire casing 32. The razor is affixed to the latter at the top or side thereof.

The casing transmits the vibrations to the hand and to the razor or directly to the latter.

The spring drive may be replaced by a motor or the like. In this event, the spring mechanism is eliminated. It is obvious that use may 55

also be made of other energy and energy-supply sources for driving purposes.

The vibratory movement may be oscillatory, rotary, uniform or irregular.

5 I claim:

1. Vibratory device for safety razors, comprising a casing which serves as a handle for the razor, a razor on said casing which includes a drive mechanism, said casing including springs arranged about a rotary shaft, means mounted on said casing for winding said springs, a gear on said shaft, a ratchet wheel adapted to be driven by said gear, a weighted pendulum adapted to contact said casing, a pawl interconnecting
- 10

said pendulum and said ratchet wheel, so that the pawl imparts an oscillatory movement to said pendulum, said weight striking against the casing wall and thus vibrating the latter and the razor.

5

2. As a new article of manufacture, a vibrating attachment for a safety razor having a handle comprising a casing, means for firmly mounting the casing upon the handle of the razor, a weighted rock arm mounted within the casing, 10 and means for rapidly oscillating said weighted rock arm to set up vibrations.

RICHARD JAFFÉ.
